FREIGHT CONTAINER

Benjamin F. Fitch, Greenwich, Conn., assignor to
Motor Terminals Company, Wilmington, Del.,
a corporation of Delaware

Application June 10, 1931, Serial No. 543,280

2 Claims. (Cl. 98—87)

In the transportation of freight, demountable automobile truck bodies, which may be bodily lifted with their contents and placed on a flat car, provides for economical handling and minimizes danger of loss or breakage of package freight. 5 For such purposes I have developed a very efficient demountable body, which forms the subject matter of my prior application Serial No. 500,160, filed December 5th, 1930.

10 Such demountable bodies may be employed for the handling of perishable goods, fruits, etc., and in such cases it is sometimes desired to provide means for continuously ventilating the container while it is in transit. The present invention is 15 concerned with very simple and effective means for causing such ventilation.

By employing hollow doors, which may be made of truss plate, instead of solid doors shown in my application referred to, and by making suitable openings through such doors, I arrange to insure a draft of air into the body, which receives its exit by means of spaces at the eaves. The openings through the doors are so arranged that any access of water to the interior through them 25 is impossible. Furthermore, the position of the discharge into the container serves to direct the incoming air over the top of the merchandise, which carries away the moisture arising therefrom, and prevents deleterious action.

30 My ventilation provision in no way interferes with the present use of the body for ordinary package freight, but makes it more adaptable in case of perishable freight. However, I provide means whereby the draft may be shut off, if it 35 should be desired to avoid the same in any particular instance.

My invention is illustrated in the drawings hereof, and is hereinafter more fully explained in connection with these drawings, and the essential features are summarized in the claims. 40

In the drawings, Fig. 1 is a side elevation of a railway flat car, carrying two of my demountable bodies, each having doors equipped with my ventilation provision. Fig. 2 is an end view of one 45 of the bodies, illustrating it as it is being lifted from or lowered onto the car. Fig. 3 is a vertical section through one of the end doors and adjacent parts of the container, as indicated by the line 3—3 on Fig. 2. Fig. 4 is a vertical section of the 50 upper portion of one of the doors. Fig. 5 is a vertical section from the interior of the container looking toward the end doors. Fig. 6 is a detail adjacent the eaves, being a vertical section substantially on the line 6—6 on Fig. 5. Fig. 7 is a 55 vertical section from the interior of the car look-

ing toward a pair of end doors of somewhat different construction. Figs. 8 and 9 are, respectively, a vertical section and a horizontal section through the doors of Fig. 7, as indicated by the corresponding lines thereon. Fig. 10 is a view of 5 the upper portion of such door as shown in Fig. 7, but illustrating a different form of draft control; Fig. 11 is a vertical section on the line 11—11 in Fig. 10.

As illustrated in Figs. 1 and 2, A indicates a 10 suitable flat car, equipped with positioning devices a, (shown as external corner brackets, though projections adapted to engage sockets beneath the container floor might be used); B indicates a demountable body adapted to be 15 placed on the car and located by means of these positioning devices.

The body B has a suitable base frame 10, composed of suitable structural shapes, this base frame carrying a flooring 11. Suitable side walls 20 12 and end walls 13 rise from the base frame and carry a roof 15, formed of corrugated metal, arranged in an arch and with the serpentine lines thereof extending longitudinally, thus presenting a succession of downwardly facing transverse 25 troughs terminating at the eaves. These roof sheets 15 are carried by suitable arched cross bars 16, secured to the side walls. The top portion of each side wall has an inwardly bent eave plate 17, lying beneath the corrugated roof, and thus 30 there are a series of ventilation spaces at the two eaves above the eave plate 17 and leading to the outside of the container. A longitudinal wooden protection strip 18 is mounted above the roof sheets in this region to prevent possible damage 35 to the edge portions of the roof sheets, or crushing of the corrugation, which might reduce the ventilation spaces.

The doors of my container designated 20, may be composed of a pair of sheets of metal 21 and 40 22, which are inwardly indented in isolated regions, the indentations being electrically welded or otherwise secured together at points where the indentations of one sheet come into contact with the facing indentations of the opposite sheet, 45 thereby making what is known as a truss plate. Around the margins of the door, wooden filler strips 25 are inserted between the two metal sheets, and such composite construction at the 50 margin is protected by a channel-shaped reinforcing metal member 26, which passes across the outer edge of the filler strip and the outer sides of the adjacent truss sheets. Suitable rivets 27, extending through the reinforcing member, 55

the truss sheets and the filler strip effectively lock the parts together, as illustrated in Fig. 4.

Doors constructed as described, are mounted on lift-off hinges 30 carried by the body walls.

- 5 The doors, when closed, occupy rabbed edges of door jambs carried by the walls, such edges being preferably provided by a Z-bar construction 31, secured to the outer face of the wall and then having an inwardly extending web, and finally a 10 projecting flange, as illustrated in Fig. 3. The edges of the doors come close to the Z-bar webs, while the inner faces of the doors adjacent the edges substantially abut the Z-bar flanges. Thus there is a substantially weathertight connection 15 between the doors and container walls.

To provide for the draft through such a container as described, without danger of damage from water, I form a set of openings 40 through the outer door sheet 21, in its lower region and a 20 set of openings 41 through the inner door sheet 22 in its upper region, so that the air may pass into the lower portion of the hollow door, upwardly in the door and then from the upper portion of the door into the container, and thence out through the eave spaces 43, provided by the corrugated roof. The inwardly discharging openings 41 are arranged on the upper portion of the door so that the draft is across the 25 top of the perishable goods within the container, where the draft is most effective in preventing deterioration.

To prevent accumulation, within the door, of water which might pass through the openings 40, I form draining openings 45 through the bottom filler strip 25 and the bottom channel member 26.

When a car carrying the bodies, having doors as described, is in motion, there will be considerable draft into the openings 40 of the end doors, which will be discharged into the body through the openings 41 and thence pass out at the sides through the eaves. There likewise will be some draft ordinarily into the side doors on one or the other side of the container, which will enter 45 the body and pass out through the eaves, and the air thus moving will provide effective ventilation for perishable goods without any chance of goods being damaged by entrance of water.

As it is sometimes desired, particularly in cold 50 weather, to close the ventilating openings in the doors, I provide each ventilated door with a suitable closure mechanism operable at will. This closure mechanism varies according to the door construction; three forms of it are shown 55 in the drawings, which will now be described.

In the doors illustrated in Figs. 3, 4 and 5, I provide within each door a closure slide 50, which stands within the door behind the discharge openings 41 and has a set of openings 60 51 which may register with the openings 41. By shoving the slide longitudinally, the openings of the slide are carried out of registration with the door openings 41, so that the latter are closed. The slide may be readily operated by 65 means of a suitable knob 53, which has a shank passing through a slot 52 in the door, the inner end of the shank being secured to the slide.

To prevent inadvertent displacement of the slide, I form the slot 52 with downward extensions at each end, as shown in Fig. 5. When the slide stands with the holes in registration, the shank occupies one of the downward extensions, and the slide remains in this position notwithstanding the movement of the container 75 until the knob is elevated and moved longitudi-

nally and replaced in the other downward extension of the slot. In the latter position the holes are out of registration and the ventilation openings are thereby closed. The slide is loosely carried by suitable clips 56, 57, secured to the inner face of the inside door sheet, these clips holding the slide against the door sheet and guiding it, but with sufficient freedom to allow it to be raised sufficiently to carry the knob shank out of the slot depressions. 10

The door of Figs. 7 to 11, inclusive, differs from that shown in the preceding figures specifically in that the depressions are staggered in successive vertical rows, clearly shown in Fig. 7. The proximity of the depressions accordingly 15 prevents the employment of such a controlling slide as shown in Fig. 5. In such case, I may accomplish the control, and also stiffen the door, by omitting the depressions in the central region of the door, and mounting therein a transverse 20 bar 60 secured to the opposite door panels and also to the vertical edge members 26, by suitable rivets indicated at 61. I make a series of holes 62 vertically through this stiffening bar, and I mount on top of the bar a sliding plate 64 25 which has openings which may register with the openings 62. A suitable handle 65, secured to the slide 64 and extending through a slot 66 in the inner door plate, furnishes means for shifting the slide lengthwise thereof, the slide being 30 locked in either extreme position by means of the handle engaging the depression at the corresponding end of the slot 66.

The construction just described makes the door stiffer and stronger, while adding very little 35 to its weight, and, at the same time, provides an effective closure operable at will from the inner face of the door.

Where it is desired to employ a truss plate door with the depressions overlapping, as in Fig. 7, without the central internal draft controller, I may control the draft by means of a plate 70 (Figs. 10 and 11) secured to the external face of the inner door plate near the top. This plate 70 has openings 71 adapted to register with the openings 41 and it may be clamped against the door with the openings in registration, or out of registration, as desired. The plate could be fastened in either position by screws, but, to enable ready adjustment without the removal of 50 any part, I may make vertical slots 72 in the plate through which pass studs 75 carried by the door and having threaded ends on which are mounted wing nuts 76. Normally, the plate 70 stands as shown in Fig. 11, with the openings 55 in registration, but, by loosening the wing nuts, it may be raised into the position shown in the dotted lines and clamped in that location by the tightening of the nuts. 60

It will be seen that whichever mounting of the controlling slide is employed, I have readily controllable openings through the door allowing the entrance of air into the lower portion of the door and its escape from the upper portion of the door into the container. The slide, being controlled in the inner side of the door, cannot be disturbed after the door is closed. My controlled ventilated door accordingly renders the container suitable for summer and winter use and for the carrying of perishable goods as well as ordinary package freight. 70

I claim:

1. A door comprising a pair of plates spaced apart, an opening from the outside through the 75

lower portion of the outer plate to the interior of the door, an opening from the upper portion of the interior of the door, a cross brace within the door between the regions of the lower and upper openings, said cross brace having an opening, a slide within the door for controlling the latter opening, and means for operating the slide.

2. A door comprising a pair of metal plates spaced apart, filler strips between the plates ad-

jacent the margins, binding strips on the outer sides of the plates and across the outer edge of the filler strips whereby an enclosed chamber is made within the door, ventilation openings in one face of the door adjacent the lower edge, 5 ventilation openings in the other face of the door adjacent the upper edge, and a draining passageway through the bottom filler strip and binding strip.

BENJAMIN F. FITCH. 10
